Primary Examiner — David G Muller(57) **CLAIM**

The ornamental design for a dental syringe cap, as shown and described.

DESCRIPTION

FIG. 1 is a perspective view of a dental syringe cap showing the new design;

FIG. 2 is a front view thereof;

FIG. 3 is a rear view thereof;

FIG. 4 is a left side view thereof, the right side view being a mirror image thereof;

FIG. 5 is a top view thereof, the bottom plan view being a mirror image thereof; and,

FIG. 6 is a perspective view of the dental syringe cap in use with a dental syringe.

The portions of the "dental syringe cap" in FIGS. 1-6 shown in broken lines are included to show features that form no part of the claimed design.

1 Claim, 5 Drawing Sheets# US D861,160 S
